UNITED STATES PATENT OFFICE.

HENRY C. SERGEANT, OF NEW YORK, N. Y.

DIRECT-ACTING ENGINE.

SPECIFICATION forming part of Letters Patent No. 430,757, dated June 24, 1890.

Application filed August 30, 1889. Serial No. 322,454. (No model.)

To all whom it may concern:

Be it known that I, HENRY C. SERGEANT, of New York, in the county and State of New York, have invented a certain new and useful Improvement in Direct-Acting Engines, of which the following is a specification.

My improvement relates to cylinder-heads in direct-acting engines, and is more particularly applicable to cylinder-heads employed with rock-drills.

I will describe in detail a cylinder-head embodying my improvement, and then point out the novel features in claims.

In the accompanying drawings, Figure 1 is a side elevation of a cylinder-head embodying my improvement. Fig. 2 is an end view of the same, looking in the direction of the arrow, Fig. 1. Fig. 3 is a transverse section taken on the line $x-x$, Fig. 4. Fig. 4 is a face view 20 of one of the members of the cylinder-head, showing a packing thereof in section.

Similar letters of reference designate corresponding parts in all the figures.

In carrying out my improvement I form a cylinder-head of two members A A', each of which is substantially semicircular and hollow. These portions, when in use, are secured together by bolts B, which extend through lugs or ears a , extending from the portions A 25 A' upon the exterior thereof. Each of the portions A A' is cast, and in it I form semicircular recesses b , which recesses, as here shown, are L-shaped in the cross-section, although I do not consider such shape to be 30 wholly essential.

In placing the members A A' together I take a packing-ring C and place it in the recess b . When the members A A' have been secured together, the packing-ring C will be firmly retained in the cylinder, which is 40 formed by both the semicircular recesses b . When the cylinder-head is used upon a rock-drill, the drill-rod passes through the packing C, and pressure acting upon the packing effectually prevents leakage.

It will be seen that by my improvement a simple and economical construction is adopted, providing a very ready means for retaining a suitable packing in place.

What I claim as my invention, and desire 50 to secure by Letters Patent, is—

1. The combination, with a divided cylinder-head composed of two members, each having formed in it a semicircular recess, of a packing-ring fitting the recesses in both said 55 members when the members are secured together, substantially as specified.

2. The combination, with a divided cylinder-head composed of two members, each having formed in it a semicircular recess, 60 which is L-shaped in the cross-section, of a packing-ring adapted to fit said recesses when the two members have been secured together, substantially as specified.

HENRY C. SERGEANT.
